DENTURE BRUSH

Frank J. Traxl, Chicago, Ill.

Application July 28, 1933. Serial No. 682,610

4 Claims. (Cl. 15—167)

The invention relates to brushes and more particularly it relates to brushes especially constructed for cleaning removable dentures, bridges, plates, or the like.

Owing to the irregular configuration of dentures and removable bridges it is difficult, if not impossible, to thoroughly clean the same with a single brush of ordinary construction and it is an object of the invention to provide a brush of improved construction and novel configuration adapting it for easy manipulation and abrasive contact with all portions of the irregular bounding surfaces of removable dentures and bridges including both relatively large curved surfaces and grooves of dentures.

Another object of the invention is the provision of a brush adapted to fit within both convex and concave surfaces such as the labial portions of dentures and is also adapted for insertion in the clasps of partial dentures in a manner to thoroughly clean the same.

A further object of the invention is the provision of a brush having a portion of its handle curved in a manner to adapt the brush for free manipulation in deep depressed surfaces of dentures without contact of the handle therewith.

A still further object of the invention is the provision of an improved brush of the kind described which is simple, economical, durable and satisfactory for its intended purpose.

Many other objects and advantages of the construction herein shown and described will be obvious to those skilled in the art from the disclosure herein given.

To this end, my invention consists in the novel construction, arrangement and combination of parts herein shown and described, and more particularly pointed out in the appended claims forming a part hereof.

In the drawing, wherein like reference characters indicate like or corresponding parts:

Fig. 1 is a view of the brush as it may be employed in cleaning the lower exposed surface of a full upper denture shown inverted from its normal position;

Fig. 2 is a longitudinal section through the brush and denture shown in Fig. 1; and

Fig. 3 is a section along the line 3—3 of Fig. 2.

Referring now more particularly to the drawing, the brush comprises a handle 10 having a substantially inclined end portion 11 providing a pair of apertures 12 at one end and a pair of bristle carrying cores respectively fixedly mounted in the apertures. The cores each comprise two lengths of wire twisted spirally and bent near

their middle portions to a generally U-shape comprising end sections 13 and 14 connected by a crook or bend 15. The rear ends of the forwardly projecting portions 13 are wedged in position in the handle apertures 12 with the corresponding free ends of the sections 14 projecting rearwardly and terminating substantially opposite to the end of the inclined handle portion 11.

A plurality of bristles 16 of substantially uniform length are clamped between the portion of the wires forming the core sections 13. The sections 13 are curved downwardly and the space between the sections is preferably slightly greater than one-half of the length of the bristles 16. As a result, the adjacent ends of the bristles 16 overlap substantially to provide a compact middle longitudinally extending portion of substantial depth and width, the upper surface of which is concave and the lower surface convex longitudinally of the brush.

Lateral concavity and convexity of the upper and lower surfaces respectively of the brush is obtained by inclining the bends or crooks 15 outwardly and upwardly and extending the sections 14 rearwardly therefrom in spaced apart relation to and above the adjacent sections 13. The sections 14 are also curved downwardly and thereby provide for extending the longitudinal concavity and convexity of the upper and lower surfaces of the middle portion of the brush to the lateral edges thereof. Bristles 17 are clamped between the wire comprising the crook 15 and the sections 14, the lengths of the bristles gradually diminishing towards the free ends of the sections 14. The spacings of the sections 14 from the sections 13 with which they are connected is preferably such that there is tangential contact or slight overlapping of the ends of the contiguous bristles 16 and 17.

As shown in Fig. 3 the core sections 14 are at an elevation such that the bristles have their upper and lower ends above the corresponding ends of the bristles 16 with the result that the top of the brush is concave laterally and the bottom is convex laterally. The described arrangement and construction of the core sections and bristles provides a brush having a top surface concave both laterally and longitudinally and a bottom surface similarly convex laterally and longitudinally.

An inverted upper denture 20 is shown in Figs. 1 and 2 which provides a raised portion 21 bounded by relatively large convex and concave surfaces adapted for contact therewith of the corresponding concave and convex brush sur-

faces. The main body portion of the handle 10 extends in the same general direction as the brush element and the length of the inclined portion 11 is such that the handle will clear 5 the teeth of the denture with the brush positioned therein with the handle extending in a direction opposite to that shown in Fig. 1 and 2.

The edge portions of the brush comprising the rearwardly extending core sections 14 and bristles 10 17 form individual small diametered curved 15 brushes adapted for insertion in bridge clamps, or the like, and also in crevices such as the denture groove 22, accessibility to which is difficult or impossible in using a brush of ordinary construction.

Thus, it will be seen that I have provided a brush of the kind described providing an upper surface which is concave both laterally and longitudinally and a lower surface which is convex 20 both laterally and longitudinally, thereby adapting the brush for use on relatively large correspondingly curved portions of a denture and which has its lateral edges providing individual 25 tapering circular brushes adapted for insertion in recesses, small grooves and other interstices of dentures and bridges, or the like, in combination with a handle having an inclined portion adapting the brush for free manipulation without 30 contact of the handle with the labial or other projecting portions of dentures.

Having thus described my invention, it is obvious that various immaterial modifications may be resorted to without departing from the spirit of the invention; hence, I do not wish to be 35 limited to the exact form, construction, arrangement and combination of parts herein shown and described, or uses mentioned.

What I claim as new and desire to secure by Letters Patent is:

40 1. A denture brush of the kind described comprising a handle and a brush element, the upper and lower surfaces of said element being respectively concave and convex laterally and longitudinally, the end of the handle adjacent the 45 brush element being inclined thereto and the remainder of said handle being substantially parallel to said element.

45 2. A brush of the kind described comprising a handle and a brush element, said element comprising a pair of generally U-shaped bristle car-

rying cores, each core having one stem mounted in the handle in spaced apart relation to the corresponding stem of the other core, the middle portion of each core being inclined outwardly and upwardly with the free end of the core extending rearwardly and terminating substantially opposite the end of the handle, and bristles so mounted on the cores that the longitudinal middle portion of the brush element is relatively thick and compact and the lateral edges are relatively thin.

50 3. A brush of the kind described comprising a handle and a brush element, said element comprising a pair of generally U-shaped bristle carrying cores, each core having one stem mounted in the handle in spaced apart relation to the corresponding stem of the other core, the middle portion of each core being inclined outwardly and upwardly with the free end of each core extending rearwardly and terminating substantially opposite the end of the handle, and bristles so arranged on said cores that the middle longitudinally extending portion of the brush element is relatively thick and compact and the lateral edge portions are thin and combine with 100 said middle portion to provide a brush having its upper and lower surfaces respectively concave and convex laterally and longitudinally.

55 4. A denture brush of the kind described comprising a handle and a brush element, said brush element comprising a pair of generally U-shaped bristle carrying cores, each having a stem mounted on the handle, the middle portion of each core being inclined outwardly and upwardly and the other stem extending rearwardly and terminating substantially adjacent the end of the handle, the middle portion of each of said stems being curved downwardly, and bristles mounted on said cores, the bristles mounted on each inner stem being of substantial length and overlapping 115 the corresponding bristles on the other inner stem, the bristles on the middle portions of outside stems of said cores gradually diminishing in length towards the free end of said stems, the length of said bristles and arrangement of said 120 cores being such that the top surface of the brush is concave both laterally and longitudinally and the bottom surface is convex laterally and longitudinally.
